UNITED STATES PATENT OFFICE.

ERIK WILHELM WALDENER, OF DUVBO, NEAR SUNDBYBERG, SWEDEN.

ROTARY REFRIGERATING MACHINE.

Application filed September 20, 1926, Serial No. 136,568, and in Sweden July 16, 1924.

The present invention relates to an improvement in such rotary refrigerating machines which consist of a cooler or refrigerator and a rotary condenser connected with said refrigerator, as well as a compressor for drawing the cooling fluid from the refrigerator and for compressing the same in the condenser, said compressor being driven during the rotation of the machine through 10 cooperation with a weight suspended in the machine but not entrained in the rotation thereof. The cooler or refrigerator rotates in the liquid or the like, for instance a solution of common salt, which it is desired to cool, and from the cooler the compressor draws the cooling fluid which, when evaporating in the cooler, takes up heat from the liquid surrounding the cooler, after which the compressor compresses said cooling fluid 20 in the condenser whereby heat is liberated which is removed, as a rule, by the condenser rotating in cooling water. The cooling fluid compressed and condensed into liquid state is again introduced into the cooler, and the 25 cooling fluid thus passes in a continuous circulation through the cooler and the condenser.

According to the present invention the compressor is located in the condenser coaxially with the axis of rotation of the machine. By this arrangement a good balancing of the machine is obtained, and also that the dimensions of the machine may be made comparatively small, whereby it becomes 35 possible to make refrigerating machines according to this invention for comparatively small cooling effects. The compressor is preferably made as a piston compressor, and in such case the piston of the compressor is located coaxially with the axis of rotation of the machine. The compressor piston is 40 preferably provided with a cam which is embraced by rollers carried by the stationary weight, so that in this manner the compressor piston will be caused to perform a 45 reciprocating movement during the rotation of the machine.

A further characterizing feature of the invention is that the suction conduit from the cooler to the compressor is quite continuous and uninterrupted, since it is formed of parts which are fixed and immovable relatively to each other, so that there can be no such leaks which are unavoidable when the

suction conduit is made up of parts movable 55 relatively to each other.

Still another feature of the invention consists in that tubes which reach close to the periphery of the condenser, are secured to the stationary weight in such manner that 60 they conduct condensed cooling fluid forced into said tubes during the rotation of the machine, to the bearing and sliding surfaces of the weight, the rollers and the compressor piston.

In the accompanying drawing an embodiment of a rotary refrigerating machine according to the invention is illustrated by way of example. Fig. 1 shows an axial section through the condenser and the cooler, and Fig. 2 shows a cross section of the condenser 70 on the broken line II-II in Fig. 1.

The machine comprises a cooler or refrigerator 1 having the shape of a hollow ball or the like which, as above mentioned, rotates in the solution of salt, or the like, which it is desired to cool. The cooler 1 is secured to a shaft 2 which supports at its other end the condenser 3 which is also supported by a second shaft 4. The shafts 2 and 4 are 80 supported in bearings 5 and 6, respectively, and to the shaft 4 a pulley 7 is attached by means of which rotational movement is transmitted to said shaft, so that the condenser 3 and the cooler 1 are caused to rotate. 85

The shafts 2 and 4 are provided at their opposing ends with enlargements 8 and 9, respectively, which carry arcuate arms 10 and 11, respectively, the ends of which overlap and are joined together by means of screws 90 12. Hemispherical caps 13 and 14 are placed outside said arms and are retained in position by means of nuts 15 and 16 screwed on to threaded portions of said enlargements 8 and 9, the adjoining edges of said caps being 95 joined by means of solder 17 or in other suitable manner. Said caps thus form together a spherical chamber which constitutes the condenser.

Each of the enlargements 8 and 9 is provided with an axial cylindrical bore 18 and 19, respectively, in each of which there is inserted a cylindrical sleeve 20 and 21, respectively, the interior of which forms a compressor cylinder. In the shaft 2 there is an axial bore or passage 22 leading from the cooler 1 to the cylinder 20 from which it is separated by a suction valve 23. The shaft

4 is also provided with an axial bore or passage 24 separated from the cylinder 21 by a suction valve 25. Said bores 22 and 24 communicate through an arcuate tube 26.

5 A piston 27 is slideable in the cylinders 20 and 21 and is provided at each end with a pressure valve 28 which closes a central passage 29 in said piston, which passage 29 communicates through a number of holes 30 with 10 the interior of the condenser 3. The piston 27 is provided with a number of longitudinal flutes or grooves 31 in which are placed balls 32 which also roll in longitudinal flutes or grooves 33 in sleeves 34 which are secured in 15 the bores 18 and 19 in the enlargements 8 and 9. Said balls 32 will thus guide the reciprocating movement of the piston and will also cause the piston to be entrained in the rotational movement of the shafts 2 and 4 20 and condenser 3. The piston 27 is also provided with a cam 35 the purpose of which is described here below.

A cage consisting of two rings 36 and 37 and two cross-pieces 38 and 39 joining said 25 rings, is supported in the condenser by means of ball bearings 40 which are placed coaxially with the axis of rotation of the condenser. A weight 41 is attached to said cage by means 30 of bolts 42. From the upper cross-piece 38 two studs 43 project downwards and support at their lower ends rollers 44 which roll against opposite sides of the cam 35 on the piston 27. Said studs 43 are screw-threaded into blocks 45 which are slideable in the axial 35 direction in the cross-piece 38, and which may be adjusted by means of screws 46 threaded into said cross-piece 38, in such manner that the rollers 44 may be caused to bear without play against the cam 35. Said 40 studs 43 are tubular, and to the upper ends of the same tubes 47 are secured which serve to conduct condensed cooling fluid from the inner circumference of the condenser through said tubes and said studs inwards to 45 the piston in order to lubricate the same. A centrally located tube 48 leads to a passage 49 in the upper cross-piece 38 and serves to conduct condensed cooling fluid to the blocks 45 from which said fluid will flow to the rollers 50 44 and lubricate these parts. Other tubes 50 are secured at the ends of the cross-piece 38 and serve to conduct condensed cooling fluid to the ball bearings 40. In the outer 55 end of each tube 47, 48, and 50 there is inserted a small partition 61 located in an axial plane, and said outer ends of the tube are cut off obliquely on both sides towards the upper edge of said partition as shown in Fig. 2, so as to provide an easy access for the cooling 60 fluid from both sides.

A tube 51 leads from the inner circumference of the condenser 3 to a passage in the enlargement 8, which passage is continued by a tube 52 located in the bore 22 in the 65 shaft 2, and the other end of which ends in a

small chamber 53 in a button 54 secured to the cooler 1. In said button 54 a nozzle 55 having a limited area of flow is inserted. The button 54 is also provided with passages 56 through which the cooling fluid discharged 70 through the nozzle 55, can flow out into the cooler 1. A screw 57 is threaded into the button 54, so that after removing said screw 57 the nozzle 55 may be detached and replaced by another nozzle in order to obtain some 75 other desired area of the outlet opening in the nozzle. On to the screw-threaded end of the shaft 2 a cap 58 is screwed which secures the cooler 1 to said shaft 2, and which is provided with apertures 59 in order to allow the 80 cooling fluid to be drawn from the cooler into the bore 22 in said shaft.

The bore 24 in the shaft 4 serves for filling the machine with cooling fluids. Said bore is closed by means of a screw 60.

When the machine is put in rotation the compressor piston 27 will be entrained by the balls 32, whereas the cage 36, 37, 38, 39 and the weight 41 will remain approximately in the position illustrated, and will thus maintain the studs 43 supporting the rollers 44 stationary with relation to the rotating parts. Since said cage is supported and guided by the ball bearings 40 and is thus prevented from movement in the axial direction, owing 90 to the engagement of the rollers 44 with the cam 35 the compressor piston 27 will be caused to reciprocate in the cylinders 20 and 21 upon rotation of the machine. The cooling fluid in the cooler 1 will therefore be 95 drawn through the apertures 59 and the bore 22 in the shaft 2 past the suction valve 23 into the cylinder 20 and also from said bore 22 through the tube 26 and past the suction valve 25 into the cylinder 21, the cooling fluid, when expanding in the cooler, taking 100 up and bringing along heat from the liquid surrounding the cooler 1. This cooling fluid is now compressed in the cylinders and is forced out of the cylinders past the pressure 105 valves 28 and through the passage 29 and holes 30 into the condenser 3, the heat thus given off being taken up by the cooling water or other medium surrounding the condenser. The compressed and condensed 110 cooling fluid is forced by the rotation out against the inner circumference of the condenser. Owing to the pressure prevailing in the condenser such condensed cooling fluid is forced through the tubes 51 and 52, the 115 chamber 53, nozzle 55 and passages 56 back into the cooler 1, the opening in the nozzle 55 being such that the correct difference of pressure is maintained between the condenser and the cooler. The chamber 53 120 serves to collect foreign particles possibly present in the cooling fluid.

During the rotation of the machine a portion of the condensed cooling fluid will be forced into the tubes 47, 48 and 50 through 125 130

which it will flow downwards and lubricate the moving parts within the condenser, as previously explained, namely the rollers 44 and the paths of said rollers on the cam 35, 5 the compressor piston 27, and the balls 32 and grooves 31 and 33 for said balls, as well as the ball bearings 40. Owing to the ends of said tubes being cut off obliquely on both sides and being provided with partitions 61, 10 the condensed cooling fuel will be forced into the tubes upon the machine rotating in any direction. As cooling fluid sulphur dioxide may be used, for instance, since in condensed state it is a good lubricant.

15 The invention is, of course, not limited to the embodiment above described and illustrated in the drawing, since it will be understood that the details of the same may be modified in various respects without departing from the principle of the invention.

I claim:

1. In a rotary refrigerating machine the combination of a rotary condenser, a compressor located within and rotated with said condenser and having a piston located coaxially with the axis of rotation of said condenser, means whereby said piston is guided axially but prevented from rotation relatively to said condenser, a weight pivotally mounted 25 in said condenser in such manner as to be substantially stationary during rotation of said condenser, means connecting said compressor piston to said weight in such manner as to cause said piston to perform longitudinal reciprocating movements during rotation of said condenser, a cooler connected to said condenser, and a suction conduit from said cooler to said compressor.

2. In a rotary refrigerating machine the combination of a rotary condenser, a compressor located within and rotated with said condenser and having a piston located coaxially with the axis of rotation of said condenser, means whereby said piston is guided 40 axially but prevented from rotation relatively to said condenser, a cam on said piston, a weight pivotally mounted in said condenser in such manner as to be substantially stationary during rotation of said condenser, 45 rollers carried by said weight and embracing said cam on said piston from opposite sides so as to cause said piston to perform longitudinal reciprocating movements during rotation of said condenser, a cooler connected to said condenser, and a suction conduit from said cooler to said compressor.

3. In a rotary refrigerating machine the combination of a rotary condenser, a compressor having a cylinder located within and rotated with said condenser, and having a piston in said cylinder located coaxially with the axis of rotation of said condenser, said piston being provided with longitudinal 50 grooves, said cylinder being provided with corresponding longitudinal grooves, balls 55 inserted in said grooves in said piston and said cylinder, said piston being provided with a cam, a weight pivotally mounted in said condenser in such manner as to be substantially stationary during rotation of said condenser, blocks adjustable in said weight, rollers carried by said blocks and embracing said cam on said piston from opposite sides so as to cause said piston to perform longitudinal reciprocating movements during rotation of said condenser, a cooler connected to said condenser, and a suction conduit from said cooler to said compressor.

4. In a rotary refrigerating machine the combination of a rotary condenser, a compressor located within and rotated with said condenser and having a piston located coaxially with the axis of rotation of said condenser, means whereby said piston is guided axially but prevented from rotation relatively to said condenser, a cam on said piston, a weight pivotally mounted in said condenser in such manner as to be substantially stationary during rotation of said condenser, 70 rollers carried by said weight and embracing said cam on said piston from opposite sides so as to cause said piston to perform longitudinal reciprocating movements during rotation of said condenser, a cooler connected to said condenser, and a suction conduit from said cooler to said compressor.

5. In a rotary refrigerating machine the combination of a rotary condenser, a compressor having a cylinder located within and rotated with said condenser, and having a piston in said cylinder located coaxially with the axis of rotation of said condenser, said piston being provided with longitudinal 80 grooves, said cylinder being provided with corresponding longitudinal grooves, balls 85 inserted in said grooves in said piston and said cylinder, said piston being provided with a cam, a weight pivotally mounted in said condenser in such manner as to be substantially stationary during rotation of said condenser, blocks adjustable in said weight, rollers carried by said blocks and embracing said cam on said piston from opposite sides so as to cause said piston to perform longitudinal reciprocating movements during rotation of said condenser, a cooler connected to said condenser, and a suction conduit from said cooler to said compressor.

6. In a rotary refrigerating machine the combination of a rotary condenser, said condenser consisting of two opposing yokes joined to one another, and two surrounding caps joined to each other and supported by said yokes, a compressor located within and rotated with said condenser and having a piston located coaxially with the axis of rotation of said condenser, means whereby said piston is guided axially but prevented from rotation relatively to said condenser, 100 a weight pivotally mounted in said condenser in such manner as to be substantially stationary during rotation of said condenser, blocks adjustable in said weight, rollers carried by said blocks and embracing said cam on said piston from opposite sides so as to cause said piston to perform longitudinal reciprocating movements during rotation of said condenser, a cooler connected to said condenser, and a suction conduit from said cooler to said compressor.

7. In a rotary refrigerating machine the combination of a rotary condenser, said condenser consisting of two opposing yokes joined to one another, and two surrounding caps joined to each other and supported by said yokes, a compressor located within and rotated with said condenser and having a piston located coaxially with the axis of rotation of said condenser, means whereby said piston is guided axially but prevented from rotation relatively to said condenser, 110 a weight pivotally mounted in said condenser in such manner as to be substantially stationary during rotation of said condenser, 115 blocks adjustable in said weight, rollers carried by said blocks and embracing said cam on said piston from opposite sides so as to cause said piston to perform longitudinal reciprocating movements during rotation of said condenser, a cooler connected to said condenser, and a suction conduit from said cooler to said compressor.

in such manner as to be substantially stationary during rotation of said condenser, means connecting said compressor piston to said weight in such manner as to cause said 5 piston to perform longitudinal reciprocating movements during rotation of said condenser, a cooler connected to said condenser, and a suction conduit from said cooler to said compressor.

10 7. In a rotary refrigerating machine the combination of a rotary condenser, said condenser consisting of two opposing yokes joined to one another, and two surrounding caps joined to each other and supported by 15 said yokes, a compressor located within and rotated with said condenser and having a piston located coaxially with the axis of rotation of said condenser, means whereby said piston is guided axially but prevented from 20 rotation relatively to said condenser, a cam on said piston, a weight pivotally mounted in said condenser in such manner as to be substantially stationary during rotation of said condenser, rollers carried by said weight and 25 embracing said cam on said piston from opposite sides so as to cause said piston to perform longitudinal reciprocating movements during rotation of said condenser, a cooler connected to said condenser, and a suction 30 conduit from said cooler to said compressor, said suction conduit being formed of relatively to each other fixed and immovable parts.

35 8. In a rotary refrigerating machine the combination of a rotary condenser, said condenser consisting of two opposing yokes joined to one another, and two surrounding caps joined to each other and supported by 40 said yokes, a compressor having a cylinder located within and rotated with said condenser, and having a piston in said cylinder located coaxially with the axis of rotation of said condenser, said piston being provided 45 with longitudinal grooves, said cylinder being provided with corresponding longitudinal grooves, balls inserted in said grooves in said piston and said cylinder, said piston being provided with a cam, a weight pivotally mounted in said condenser in such manner 50 as to be substantially stationary during rotation of said condenser, rollers carried by said weight and embracing said cam on said piston from opposite sides so as to cause said piston to perform longitudinal reciprocating 55 movements during rotation of said condenser, a cooler connected to said condenser, and a suction conduit from said cooler to said compressor,

pressor, said suction conduit being formed of relatively to each other fixed and immovable parts.

60 9. In a rotary refrigerating machine the combination of a rotary condenser, said condenser consisting of two opposing yokes joined to one another, and two surrounding caps joined to each other and supported by 65 said yokes, a compressor located within and rotated with said condenser and having a piston located coaxially with the axis of rotation of said condenser, means whereby said piston is guided axially but prevented from 70 rotation relatively to said condenser, a cam on said piston, a weight pivotally mounted in said condenser in such manner as to be substantially stationary during rotation of said condenser, blocks adjustable in said weight, 75 rollers carried by said blocks and embracing said cam on said piston from opposite sides so as to cause said piston to perform longitudinal reciprocating movements during rotation of said condenser, a cooler connected to 80 said condenser, and a suction conduit from said cooler to said compressor, said suction conduit being formed of relatively to each other fixed and immovable parts.

85 10. In a rotary refrigerating machine the combination of a rotary condenser, said condenser consisting of two opposing yokes joined to one another, and two surrounding caps joined to each other and supported by 90 said yokes, a compressor having a cylinder located within and rotated with said condenser, and having a piston in said cylinder located coaxially with the axis of rotation of said condenser, said piston being provided with longitudinal grooves, said cylinder being provided with corresponding longitudinal 95 grooves, balls inserted in said piston and said cylinder, said piston being provided with a cam, a weight pivotally mounted in said condenser in such 100 manner as to be substantially stationary during rotation of said condenser, blocks adjustable in said weight, rollers carried by said blocks and embracing said cam on said piston from opposite sides so as to cause said 105 piston to perform longitudinal reciprocating movements during rotation of said condenser, a cooler connected to said condenser, and a suction conduit from said cooler to said compressor, said suction conduit being 110 formed of relatively to each other fixed and immovable parts.

ERIK WILHELM WALDENER.
